United States Patent Office.

FRANKLIN BALL, OF WILTON JUNCTION, IOWA.

Letters Patent No. 76,582, dated April 14, 1868.

IMPROVEMENT IN WINDOW-SASH STOP.

The Schedule referred to in these Letters Patent and making part of the same.

TO ALL WHOM IT MAY CONCERN:

Be it known that I, FRANKLIN BALL, of Wilton Junction, in the county of Muscatine, and State of Iowa, have invented a new and improved Window-Catch; and I do hereby declare that the following is a full and exact description thereof, reference being had to the accompanying drawings, forming a part of this specification, in which—

Figure 1 is a perspective view of a portion of a window-frame with my improved catch attached thereto. Figure 2, a central vertical section through line $x\ x$, fig. 1.

Figure 3, vertical section in line $y\ y$ of fig. 1, illustrating by red lines the movement of the cam; and

Figure 4 an elevation of the face-plate and shaft detached.

Similar letters indicate like parts in all of the figures.

The nature of my invention consists of an improvement in that class of window-catches having a cam placed in a recess in the window-casing to bear against the edge of the sash, by causing the shaft operating said cam to work loosely through the same, and combining a lug on the outer end of the shaft with a complementary recess in the plate on the outer face of the casing, through which the shaft projects.

In the accompanying drawings, A represents the window-catch placed in a recess, B, cut in the window-casing C to receive it. D, a shaft, made square, hexagonal, or of an otherwise angular section, which extends from the outer or front face of the casing to the catch A, and passes loosely through an aperture therein, so formed as to embrace it closely. E is a face-plate secured upon the window-casing, through which the outer end of the shaft projects. The portion of the shaft passing through the face-plate is rounded, and a lug, F, figs. 1 and 2, is formed or cast thereon, to engage in a notch, G, figs. 1 and 4, cut in the aperture in said plate to receive it. A series of radiating-notches, H, may also be formed upon the plate, to receive and engage the inner edge h of the button or thumb-piece K of the shaft, and secure the shaft in any given position.

The curved face of the catch A is eccentric to the axis of the shaft D, which passes loosely through it. It is left plain at its central or narrowest point, to permit the window to pass freely up and down, and is notched towards its extremities, a a, to catch and hold the window when they are pressed against it, (see fig. 3.) This is effected by turning the shaft D, by means of its thumb-piece K. When the catch is to be turned, its shaft D is drawn out slightly, so that the lug F thereon may turn freely in front of the face-plate. By thus turning the shaft, the eccentric is brought to bear firmly against the edge of the sash o, fig. 3, and by then pushing in the shaft, and thus causing the lug F to engage with the notch G, the eccentric is kept in its locking position, (illustrated by red lines in fig. 3,) and the window thus secured against further movement up or down until the eccentric is released. The locking of the window is facilitated by means of the notch H formed upon the face-plate E. By pushing in the shaft D sufficiently to enable the lug F to pass out of the engaging-notch G, it may turn freely back of the plate E; but if pushed in yet farther, (as indicated in red lines, fig. 2,) the inner edge of the thumb-piece K may be made to engage with any one of said notches, (see fig. 4,) and thus secure the eccentric against the sash with any degree of pressure.

Having thus fully described my invention, what I claim therein as new, and desire to secure by Letters Patent, is—

The combination of notches H H with the face-plate and thumb-piece K of a shaft, D, and catch A of a window-fastener, all substantially in the manner and for the purpose herein set forth.

The foregoing application of my improved window-fastener signed by me, this 28th day of October, A. D. 1867.

FRANKLIN BALL.
